AUTOMATIC TRAIN CONTROL.

Application filed April 16, 1923. Serial No. 631,097.

This invention relates to railway train control systems particularly those in which there is both automatic and manual control and more especially those in which there is also providing means for indicating and recording, at a central station, the movement of trains.

The improvement consists in controlling fixed signals displayed along the track by means of a track circuit, but certain signals only are so controlled by the track circuit while others are displayed along the track without being subject to the track circuit control.

15 The object of the invention is to provide a central signal system by which certain signals may be given to trains independent of track circuit control and other signals may be given dependent upon track circuit control.

20 Other objects and advantages will appear as the description of the invention progresses and the novel features will be particularly pointed out in the appended claims.

25 In describing the invention in detail, reference is had to the accompanying drawing wherein I have illustrated a preferred physical embodiment of my invention and wherein like characters of reference designate corresponding parts throughout the several views and in which:

30 Figure 1 is a schematic representation of the apparatus and circuits in the dispatcher's office and along the track; Fig. 2, is a modification of Fig. 1 showing the apparatus and circuits along the track.

35 Fig. 1 shows a track consisting of track rails 1 and 2. Rail 1 is electrically continuous and rail 2 is divided into sections by means of insulating joints as 3, thus dividing the track into blocks. Near one end of each block is a track battery as 4 and near the other end of each block is a track relay as 5, constituting with their connections to the rails, a track circuit well known to those skilled in the art. Track relay 5 controls three armatures as 6, 7 and 8. When track relay 5 is energized, armature 7 makes contact with front contact 10 and when track relay 5 is deenergized, armature 6 and 8 make contact with back contact 11 and 12.

40 In Fig. 1 are shown six signals for each block designated as No. 1, 2, 3, 4, 5 and 6. These signals are erected along the trackway 45 in the usual manner so as to be easily visible to an engineer on an approaching train.

These signals are controlled by the several positions of the armatures of a polarized relay, as 13, and an alternating current relay, as 14, both of which are located along the 50 trackway suitably housed. In the dispatcher's office are corresponding relays, a relay, as 15, and an alternating current relay, as 16. The armatures of relays 15 and 16 control two perforating magnets, as 17 and 18. The perforating magnets are for the purpose of making a record and indication of the movement of trains and their operation will be more fully described hereinafter.

55 By means of manually operable switches 19 and 20 in the dispatcher's office, relays 13 and 15 and alternating current relays 14 and 16 are energized through three different circuits: the positive direct current circuit; the negative direct current circuit; and the 60 alternating current circuit.

65 The positive direct current circuit is as follows: from positive pole of battery 21 in the dispatcher's office, wire 24, impedance coil 25, bus 26, wire 27, spring contact 28, manually operable switch 19, wire 29, relay 15, wire 30, impedance coil 31, wire 32, line wire 33, to terminal 34, resistance 35, wire 36, terminal 47, wire 38, impedance coil 39, wire 40, polarized 70 relay 13, wires 41 and 42 to track rail 1 and thence by wires 43 and 44 to negative pole of battery 21.

75 The negative direct current circuit is as follows: from positive pole of battery 22, wires 45, 46, and 43 to track rail 1, wires 42 and 41, polarized relay 13, wire 40, impedance coil 39, wire 38, terminal 37, wire 36, resistance 35, terminal 34, line wire 33, wire 32, impedance coil 31, wire 30, relay 15, wire 29, switch 19, spring contact 47, wire 48, bus 49, impedance coil 50, and wire 51 to the negative pole of battery 22.

80 The alternating current circuit is as follows: the alternating current source 23 in the dispatcher's office, wire 52, condenser 53, bus 54, spring contact 55, switch 20, wire 56, alternating current relay 16, wire 57, condenser 58, wire 59, line wire 33, terminal 34, resistance 35, wire 36, terminal 37, and 85 thence through condenser 60, alternating current relay 14, wires 61 and 42 to track rail 1 and thence through wires 43 and 46 to alternating current source 23.

90 Impedance coils 25, 50 and 31 and 39 are 95 inserted to prevent the flow of alternating current through the circuit in which they are

inserted, and condensers 53, 58 and 60 to prevent the flow of direct current through the circuits in which they are inserted. Resistance 35 is inserted in the circuit to decrease the flow of current through polarized relay 13 and alternating current relay 14 for a purpose to be explained hereinafter.

By means of the three hereinbefore described circuits, depending upon the position 10 of the manually operable switches 19 and 20, six different electrical conditions can be established in the relays 13 and 14 along the track as follows:

First condition.—When switch 19 is in 15 contact with spring contacts 28 and switch 20 is in contact with spring contact 55, polarized relay 13 is positively energized and alternating current relay 14 is also energized.

Second condition.—When switch 19 is in contact with contact spring 47 and switch 20 is in contact with spring contact 55, polarized relay 13 is negatively energized and alternating current relay 14 is also energized.

Third condition.—When switch 19 is in contact with spring contact 28, when switch 20 is open, polarized relay 13 is positively energized but alternating current relay 14 is deenergized.

Fourth condition.—When switch 19 is in contact with spring contact 47, and switch 20 is open, polarized relay 13 is negatively energized but alternating current relay 14 is deenergized.

Fifth condition.—When switch 19 is open, that is not making contact with either spring contacts 28 or 47 and switch 20 is making contact with spring contact 55, polarized relay 13 is deenergized but alternating current 40 relay is energized.

Sixth condition.—When switches 19 and 20 are both open, relays 13 and 14 are both deenergized.

I will now describe the operation of signals No. 1, 2, 3, 4, 5 and 6 depending upon the several conditions of polarized relay 13 and alternating relay 14: Signal No. 1: When polarized relay 13 is energized with positive direct current and alternating current relay 14 is energized with alternating current, neutral armatures 62 and 63 of relay 13 make contact with front contacts 64 and 65 and polarized armatures 66 and 67 of relay 13 are in the right hand position, thus 45 making contact with contacts 68 and 69.

Armature 70 of relay 14 makes contact with front contact 71. This position of the several armatures establishes a circuit through signal No. 1 as follows: from battery 72, wires 73 and 74, armature 70, front contact 71, wire 75, armature 62, front contact 64, wire 76, polarized armature 66, contact 68, wire 77, armature 7, of track relay 5, front contact 10, wire 78, signal No. 1, wire 79, to 55 the other side of battery 72.

Signal No. 2.—When polarized relay 13 is energized with negative direct current and alternating current relay 14 is energized with alternating current, neutral armatures 62 and 63 of relay 13 make contact with front contacts 64 and 65 but polarized armatures 66 and 67 are now in the left hand position and make contact with contacts 80 and 81. Armature 70 of relay 14 makes contact with front contact 71. This position of the several armatures establishes a circuit through signal No. 2 as follows: from battery 72, wires 73 and 74, armature 70, front contact 71, wire 75, armature 62, front contact 64, wire 76, polarized armature 66, contact 80, wire 82, signal No. 2, and wire 79 to the other side of battery 72.

Signal No. 3.—When a polarized relay 13 is energized with positive direct current and alternating current relay 14 is deenergized, 85 neutral armatures 62 and 63 of relay 13 make contact with front contacts 64 and 65, and polarized armatures 66 and 67 are in the right hand position making contact with contacts 68 and 69, and armature 70 of relay 14 makes contact with back contact 83. This position of the several armatures establishes a circuit through signal No. 3 as follows: from battery 72, wires 73 and 74, armature 70, back contact 83, wire 84, armature 63, front contact 65, wire 85, polarized armature 67, contact 69, wire 86, signal No. 3, and wire 79, to the other side of battery 72.

Signal No. 4.—When polarized relay is energized with negative direct current and 100 alternating current relay 14 is deenergized, neutral armatures 62 and 63 of relay 13 makes contact with front contacts 64 and 65 and polarized armatures 66 and 67 are in the left hand position making contact with contacts 80 and 81. Armature 70 of relay 14 makes contact with back contact 83. This position of the several armatures establishes a circuit through signal No. 4 as follows: battery 72, wires 73, and 74, armature 70, 110 back contact 83, wire 84, armature 63, front contact 65, wire 85, polarized armature 67, contact 81, wire 87, signal No. 4, and wire 79 to the other side of battery 72.

Signal No. 5.—When polarized relay 13 115 is deenergized and alternating current relay 14 is energized with alternating current, neutral armatures 62 and 63 of relay 13 make contact with back contacts 88 and 89. Armature 70 of relay 14 makes contact with front contact 71. This position of the several armatures establishes a circuit through signal No. 5, as follows: from battery 72, wires 73 and 74, armature 70, front contact 71, wire 75, armature 62, back contact 88, wire 90, signal No. 5, and wire 79 to the other side of battery 72.

Signal No. 6.—When polarized relay 13 is deenergized and alternating current relay 14 is also deenergized, neutral armatures 62 and 130

63 of relay 13 make contact with back contacts 88 and 89. Armature 70 of relay 14 makes contact with back contact 83. This position of the several armatures establishes 5 a circuit through signal No. 6 as follows: from battery 72, wires 73 and 74, armature 70, back contact 83, wire 84, armature 63, back contact 89, wire 91, signal No. 6, and wire 79 to the other side of battery 72.

10 It will thus be seen that the dispatcher may display any one of the six signals by the several positions of the manually operable switches 19 and 20. The difference however, between this invention and the invention 15 shown in my application Serial No. 618,193, filed February 10, 1923, consists in that only safety signals No. 1 and No. 6 are also automatically controlled by a track circuit but facility signals Nos. 2, 3, 4 and 5 20 are independent of such track circuit control. This is accomplished by taking the circuit through signal No. 1 through armature 7 of track relay 5 and establishing a branch circuit through signal No. 6 by armature 8 of track relay 5. The automatic control of signals Nos. 1 and 6 by means of a track circuit, operates in the following manner: As long as there is no train in the block ahead 25 track relay 5 is energized and armature 7 makes contact with front contact 10. Thus the circuit through signal No. 1 is closed at front contact 10, therefore signal No. 1 will be under the full control of the dispatcher by means of switches 19 and 20, but when 30 there is a train in the block ahead, the energy from track battery 4 is short circuited through the wheels and axles of the train in a manner well-known to those skilled in the art, and the track relay is therefore not sufficiently energized to maintain its armatures 35 in the position to make contact with front contact 10. Consequently armatures 6, 7 and 8 drop, the front contact 10 is broken and armatures 6 and 8 make contact with 40 back contacts 11 and 12. When track relay 5 is thus deenergized, the circuits through signal No. 1 is opened at contacts 10 and armature 7 thus extinguishes signal No. 1, but a new circuit is established through signal No. 6 as follows: from battery 72, wires 45 73 and 93, armature 8 of track relay 5, back contact 12, wire 94, signal No. 6, and wire 79 to the other side of battery 72.

50 It will thus be seen that the dispatcher can display any one of the six signals by placing switches 19 and 20 in their several positions but when there is a train in the block ahead, signal No. 1 is automatically annulled and signal No. 6 is displayed instead.

55 Devices Nos. 1, 2, 3, 4, 5 and 6 are merely schematic and may be signal lamps which are lighted when their respective circuits are closed, or they may be translating devices such as relays by which circuits are con-

trolled to operate semaphore signals or any other electrical device, in a manner well known to those skilled in the art.

60 While in the preferred form of my invention, I have shown means to control signals Nos. 1 and 6 only, automatically by a track circuit, it is obvious that I do not mean to exclude a construction in which any of the six signals instead of 1 and 6 or in addition to them may also be automatically controlled by a track circuit by taking the circuit through any one of the six signals through an armature of a track relay.

65 I will now describe the recording apparatus in the dispatcher's office for recording the progress of trains over the division. A record sheet, as 95, is suitably mounted and driven by a roller, as 96, which in turn is driven by a shaft, as 97. Shaft 97 receives motion through ratchet wheel, as 98. A pawl, as 99, is pivotally connected to armature 100 of electro-magnet, as 101. Armature 100 is hinged at 102. When electro-magnet 101 is periodically energized, motion is given to ratchet wheel 98 through pawl 99. 70 A spring as 103 normally pulls armature 100 and pawl 99 to the right, when electro-magnet 101 is not energized. Electro-magnet 101 is connected by wire 104 to a make-and-break device, as 105, which make-and-break device is periodically operated by clock, as 106, this may well be of the form as shown in my prior Patent No. 1,203,146, granted October 21, 1916. When the make and break device is closed, the electro-magnet 101 is energized 75 through the following circuit: battery 107, wires 108 and 109, electro-magnet 101, wire 104, make-and-break device 105, wires 110 and 111, to the other side of battery 107. The make-and-break device is operated, say 80 every five seconds, by the clock 106, so as to give a slow and uniform movement to record sheet 95 through ratchet wheel 98 and pawl 99.

85 The record sheet 95 is transversely divided into sections as 112 and 113, each section representing a block along the track. Longitudinally the record sheet is divided into time lines, as 1.00 a. m., each one of the lines representing a one minute interval. Since 90 the make-and-break device 105 is operated continuously, it will be seen that longitudinally the record sheet assumes a constantly changing position during the 24 hours of the day.

95 Adjacent to the record sheet 95 are perforating magnets 17 and 18 for each space representing a block upon the record sheet. Pivotally attached to armatures 114 of these perforating magnets, are perforating needles 100 as 115, so positioned adjacent to the record sheet that when a perforating magnet is energized, a perforation is made on the record sheet. The circuit through perforating magnets 17 is controlled by armature 116 105 110 115 120 125 130

of relay 15 and the circuit through perforating magnet 18 is controlled by armature 117 of alternating current relay 16.

When switch 19 is in contact with either 5 spring contacts 28 or 47, and there is no train in the block ahead, current is flowing through relay 15 but this current is not sufficient by reason of resistance 35 in the main circuit, to attract armature 116 so as 10 to close front contact 118 and therefore the circuit through perforating magnet 17 is not closed. If, however, there is a train in the block, track relay 5 becomes deenergized and armature 6 of track relay 5 es- 15 tablishes a shunt-circuit, which cuts out resistance 35 as follows: from terminal 34 in the main circuit, wire 119 armature 6 of track relay 5, back contact 11, wires 120 and 42 to track rail, and with resistance 35 thus 20 cut out in the circuit, there is sufficient current flowing through relay 15 to attract the armatures 116 and close front contact 118. When this occurs a circuit is closed through 25 perforating magnet 17 as follows: from battery 107, wires 108 and 121, metallic contact plate 122, bus 123, wire 124, perforating magnet 17, wire 125, front contact 118, armature 116, wires 126 and 111, to the other side 30 of battery 107.

Similarly when switch 20 is in contact with spring contact 55 and there is no train in the block, current is flowing through relay 16, but this current is not sufficient by 35 reason of resistance 35 in the circuit to attract armature 117, so as to close front contact 127, and therefore the circuit through 40 perforating magnet 18 is not closed. If, however, there is a train in the block, track relay 5 becomes deenergized and armature 6 of track relay 5 establishes the same shunt- 45 circuit as hereinbefore described, thus cutting out resistance 35. With resistance 35 thus cut out of the circuit, there is sufficient current flowing through relay 16 to attract the armature 117 and close front contact 127. When this occurs a circuit is closed 50 through perforating magnet 18 as follows: from battery 107, wires 108 and 121, metallic contact plate 122, bus 123, wire 124, perforating magnet 18, wire 128, front contact 127, armature 117, wires 129, and 111, to the other side of battery 107.

It will thus be seen that when switch 19 is in contact with either spring contact 28 or 47 and there is a train in the block, perforating magnet 17 will make a perforation on the record sheet, and when switch 20 is in contact with spring contact 55 and there is a train in the block, perforating magnet 18 will make a perforation on the record sheet.

It will thus be seen that the circuit through the perforating magnets 17 and 18 is taken through a circuit breaking device 122 so that this circuit is periodically made

and broken. This circuit breaking device operates as follows: Metallic contact plate 122, is attached to armature 100 and insulated therefrom and every time the electromagnet 101 is energized, which as hereinbefore stated, is, say every five seconds, the contact through wire 121 and bus 123 is closed through the metallic plate 122. When magnet 101 is deenergized, armature 100 is pulled to the right by spring 103 and the circuit through wire 121 and bus 123 is broken. By reason of this periodic breaking of the circuit through perforating magnets 17 and 18, a continuous perforation is made on the record sheet, as long as the block is occupied. It will thus be seen that when a train enters a block, and either of the switches 19 or 20 are closed, either perforating magnet 17 or 18 commences to perforate, thus recording the exact time when a train enters a block and the perforating magnet continues to perforate until the train has left the block, thus recording the length of time the train remained in the block.

The modification as shown in Fig. 2, consists in that a seventh signal is added in addition to the six signals shown in Fig. 1 and are designated as Nos. 1, 2, 3, 4, 5, 6 and 7. The operation of signals Nos. 1, 2, 3, 4, 5 and 6 is identical as that shown and described in Fig. 1, but instead of establishing a branch circuit through signal No. 6 when the block ahead is occupied, a new circuit is established through signal No. 7, when the block is occupied as follows: from battery 72, wires 73 and 93, armature 8 of track relay 5, back contact 12, wire 130, signal No. 7 and wire 79, to the other side of battery 72. With this arrangement the engineer of the train will know that when signal No. 6 is displayed to him, that this signal was displayed from the dispatcher's office, but when signal No. 7 is displayed, he will know that it is by reason of the block ahead being occupied.

The purpose of the invention is first of all to provide instrumentalities or signals to make the operation of trains safe, but in addition to provide instrumentalities or signals which will enable the dispatcher to facilitate the movement of trains, for instance, signal No. 1 and signal No. 6, or 1 and 7 may be used for safety purposes, signal 1 indicating a clear track ahead and signals 6 or 7 indicating danger or stop. The other signals may be used for facility purposes, such as indicating to the engineer to stop at the next siding and remain on the main track, or to stop at the next siding and pull into the siding, or to stop at the next station and report to the dispatcher, or listen in on his wireless telephone. Any of the seven signals may be used as designated by the executive officers of the railway. Some of the signals, particularly those for safety pur-

poses, may be automatically controlled by a track circuit in addition to the dispatcher's control, while others of the signals particularly those used for facility purposes may be 5 independent of track circuit control, but only subject to the dispatcher's control.

It is also to be understood that relay 5 and the associated mechanism represents the construction at one block or section only, and 10 such construction will be duplicated for each block or section desired.

Although I have particularly described the construction of one physical embodiment of my invention and explained the operation 15 and principle thereof; nevertheless, I desire to have it understood that the form selected is merely illustrative, but does not exhaust the possible physical embodiments of the idea of means underlying my invention.

20 What I claim as new and desire to secure by Letters Patent of the United States, is:

1. In a railway train control system, in combination: a trackway; means dividing the trackway into electrically isolated sections; a group of more than two signals for each section; a central station; means at the central station operative in connection with sources of current and connecting with a corresponding group of signals for selectively displaying one signal of the group; a track relay for each section and means operative through the track relay when the corresponding section is occupied by a car for affecting the operativeness of the control of 25 certain of said signals by said central station means without affecting the operativeness of the control of the remainder of said signals by said central station means.

2. In a railway train control system, in combination: a trackway; means dividing the trackway into electrically isolated sections; a group of more than two signals for each section; a central station; means at the 30 central station operative in connection with

sources of current and connecting with a 45 corresponding group of signals for selectively displaying one signal of the group; a track relay for each section and means operative through the track relay when the corresponding section is occupied by a car for affecting 50 the operativeness of the control of certain of said signals by said central station means without affecting the operativeness of the control of the remainder of said signals by said central station means, said 55 track relay being also operative when its corresponding section is occupied by a car to produce a danger signal operation in said group.

3. In a railway train control system, in 60 combination: a trackway; means dividing the trackway into electrically isolated sections; a group of more than two signals positioned along the trackway in relation to each section; means at the central station 65 operative in connection with sources of current and connecting with a corresponding group of signals for selectively displaying one signal of the group; a track relay for each section and means operative through 70 the track relay when the corresponding section is occupied by a car for affecting the operativeness of the control of certain of said signals by said central station means without affecting the operativeness of the 75 control of the remainder of said signals by said central station means.

4. In a railway train control system, in combination: a trackway; means dividing the trackway into electrically isolated sections; a group of more than two signals for each section; a track relay for each section; a central station; means at the central station 80 for selectively operating the signals of each group; and means for additionally and automatically controlling only a part of the signals of each group from said track relay.

PAUL J. SIMMEN.
